UNITED STATES PATENT OFFICE

FRANK R. HIGLEY, OF CLEVELAND HEIGHTS, OHIO

INTERNAL COMBUSTION ENGINE

Application filed January 14, 1928. Serial No. 246,795.

This invention relates to internal combustion engines and more particularly to such engines of the type having a valve arranged for rotation in each cylinder thereof. Generally, the invention herein comprises improvements in the valve and arrangement set forth in my co-pending application, Serial No. 231,025, filed November 4, 1927, to which reference may be had.

10 The objects of the present invention are briefly to provide a simplified port arrangement, to provide an improved form of combustion chamber in connection therewith, to provide means for protecting the cylinder wall portion adjacent the exhaust port, to provide improved means for mounting the valve and particularly for actuating the valve, whereby improved port opening and closing characteristics may be obtained, and 15 to provide an improved cylinder block arrangement whereby the upper half of the crank case of the engine may, if desired, be cast integral with the cylinder block.

Further objects and advantages of my 20 invention will be apparent from the following description taken in connection with the accompanying drawings, in which Fig. 1 is a transverse sectional elevation taken through the center line of one of the 25 cylinders of an engine in which my invention is incorporated, as along the line 1—1, Fig. 2, parts being broken away to show details of construction; Fig. 2 is a horizontal section through three of the cylinders 30 of the engine in the plane of the valves, as in the plane of line 2—2, Fig. 1, and showing in dot-dash lines the location of the spark plugs in the cylinders; Fig. 3 is a similar horizontal section through the valve 35 actuating means as in the plane of line 3—3, Fig. 1, parts of one of the ring gears being broken away to show details of the supporting means therefor; Fig. 4 is a vertical longitudinal section taken as in the 40 plane of line 4—4, Fig. 2, but with the valves removed; Fig. 5 is a development of that portion of the cylinder surface included in Fig. 1, showing arrangement and details of portions of the valve actuating 45 and supporting means, and in dot-dash

lines the relative position of the valve ports overlying said surface; Fig. 6 is a transverse sectional elevation of a portion of the engine showing an optional form of cylinder head providing a modified form of combustion chamber, this view corresponding to that of Fig. 1 but showing the valve positioned as at the instant of ignition; Fig. 7 is a view looking upwards upon the parts as indicated in Fig. 6; Figs. 8 to 11 inclusive are detail views showing a modified form of valve driving connection; Figs. 8 and 9 being in horizontal section, Fig. 10 in vertical section and Fig. 11 being in elevation as looking radially outwards of the valve.

With reference now to the drawings, the principal parts of the engine and their arrangement are generally similar to the disclosure of my co-pending application, to which reference has been made, and comprise a cylinder block 1 having integral therewith water jacket walls 2 and preferably a portion 3 forming the upper half of the crank case, as is common practice in the art. The block 1 is provided with a number of cylinder bores or "cylinders" 5, 5', 5" and so on, these bores extending vertically through the upper portion of the block and through an integral bearing portion 6 supported as by webbing 7, a number of pillars 8 extending upwards of the webbing 7 and to webs 9 which form the lower closure members of the water jacket portion of the block. Each cylinder has a peripheral opening between the members 9 and 7 as indicated at 10 for a purpose to be described, and the block has a longitudinal opening 48 extending along one side adjacent the openings 10.

Each cylinder has three ports 11, 12, 13, (11', 12', 13', 11'', 12'', 13'') adjacent its head end, all of the ports lying on one side of the common diametrical plane and leading each through a suitable passage indicated as at 14, 15, 14', 15', 15'', 16, 16', and so on, to a lateral face 17 of the block adjacent ports of each pair of cylinders leading through the common passage 14, 16 as indicated, Fig. 2. The cylinder ports are longitudinally elongated and circumferentially

- spaced in the head end of the cylinder walls. The passages 15 are directed upwards and terminate in face 17 in generally equilateral openings as indicated, Figs. 1 and 4, and the 5 passages 14 and 16 are directed somewhat downwards and terminate also in equilateral openings. The arrangement of the openings of these passages in the face 17 is such that an intake manifold may conveniently 10 have connection between a carburetor and the passages 14 and 16, and an exhaust manifold have connection with the passages 15, all as will be understood by one familiar with the art.
- 15 The cylinders 5 terminate upwardly in the upper face 18 of the cylinder block, upon which is seated a gasket 19. For each cylinder a head member, or "cylinder head" 20, is provided, having a flange 21 seating on 20 the gasket 19 peripherally of the cylinder and thus secured, as by bolts 22. Each cylinder head has an opening 23 adapted to receive the usual spark plug, and extending about and upwards thereof a portion 24, the 25 upper extremity of which is threaded to receive a nut 25. A water jacket closure member 26, apertured to receive the portions 24 of the cylinder heads and adapted to seat peripherally of the cylinder block upon 30 the gasket 19, is maintained as shown in Fig. 1 by the nuts 25 of the several cylinder heads. It will be understood that a water inlet through the jacket wall 2 and a water outlet through the member 26 is provided 35 whereby circulation of cooling water may be maintained in the usual manner.
- Within each cylinder is a sleeve valve 27. In each valve is arranged for reciprocal movement between the dot-dash lines 28 40 and 29, a piston 50, having connection through a wrist pin 51 and connecting rod not shown, with the crankshaft of the engine, the same being of well known construction and arrangement.
- 45 Each cylinder head has a depending portion 30 extending within its valve and terminating in a transverse face 31 just clearing the head of its piston in highest position. The depending portion of each 50 cylinder head is cut away, as shown in Figs. 1 and 2, to form a face 32 extending longitudinally of the cylinder and of curvature corresponding with the inner surface of the valve, the remaining depending 55 cylinder head portion masking that portion of the valve at the elevation of the cylinder ports and not overlying the cylinder port area. Each valve has three equi-spaced ports 33 located in the plane of the cylinder 60 ports. The cylinder ports 11 and 13 are spaced correspondingly with the valve ports, whereby they will be opened and closed simultaneously by successive pairs of valve ports. Both the cylinder ports and valve 65 ports are of substantially equal longitudinal

dimension. As shown the cylinder ports 11 and 13 are somewhat less in lateral dimension than are the valve ports and the cylinder ports 12 are somewhat greater in lateral dimension. It will be understood, 70 however, that the exact spacing and dimensions of the cylinder ports relative to those of the valve ports may vary somewhat from the showing herein in accordance with engine operating characteristics desired. 75

The lower portion of each valve extends downwards through its cylinder bore and projects below the corresponding bearing member 6 of the cylinder block, as indicated in Fig. 1; and is provided with three 80 equally spaced circular openings 34, notched upwardly as indicated at 35, the notches 35 forming slots extending longitudinally of the valve.

Seating upon each bearing portion 6 of 85 the cylinder block is a ring 38 having spaced at 120° apart three radial generally circular notches 36. In each notch is a roller 37, a portion less than 180° of which projects above the upper surface of the ring 38, each 90 roller having a portion of its inner end bearing against the valve below the plane of the openings 34 whereby inward radial movement of the rollers is prevented. About each ring 38 is a circular clip or band 40 95 which serves to prevent outward radial movement of the rollers. The rings 38 are secured from rotation in any convenient manner, preferably so that the relative positioning of the rollers is the same for each 100 cylinder and as indicated in Fig. 3.

Seating upon the rollers about each valve is a ring gear 41 having teeth 42, and the lower surface of which is finished to form a cam 43 bearing on the rollers. Each ring 105 gear is provided with three equally spaced inwardly extending circular depressions 44, of diameter corresponding to that of the valve openings 34.

In each depression 44 fits an enlarged 110 cylindrical head portion of a plug or button 39 having a concentric key portion of smaller diameter projecting inwards to engagement with the valve 27 in one of the notches 35, whereby each valve is supported by its ring gear and is in driven relation therewith. Inward radial movement of each set of three buttons is prevented by engagement of their head portions with the outer valve surface, and the length of the key portions 115 is slightly less than the valve thickness whereby they underlie the inner valve surface and will thus clear the piston moving therealong. 120

The cylinders are preferably so spaced 125 that the teeth of each alternate adjacent pair of ring gears 41 mesh as indicated in Fig. 3. Longitudinally extending along and within the cylinder block and in the plane of the ring gears 41 is a shaft 45. On this shaft 130

opposite each ring gear is a pinion 46 meshing therewith. The pinions 46 are non-rotatably secured on the shaft by keys 47 lying between those pinions meshing with intermeshing ring gears. The arrangement 5 of the interengagement between the pinions and the keys is fully described in my co-pending application, to which reference has been made, and it is sufficient here to state that each pair of keys serves as spacing 10 means between its pair of pinions whereby the pinion pair may move as a unit longitudinally of the shaft 45 so as to equalize tooth loads between each pinion of the pair 15 and its ring gear. The teeth of the ring gears and of the pinions are helically arranged, preferably at 45° as indicated, and the direction of rotation of the pinions is clockwise, Fig. 1, whereby the thrust of the 20 teeth will tend to maintain each pinion in abutting relation with its adjacent keys, and likewise will tend to maintain each ring gear seating upon its set of rollers 37.

The operation of the engine will be as follows: Briefly, rotation of the crank, not 25 shown, is effected in the usual manner by explosion pressures generated in timed relation in the combustion chambers of the several cylinders and acting upon the piston heads, as will be well understood by one familiar with the art. The shaft 45 has suitable connection with the crankshaft to be driven thereby in a clockwise direction, Fig. 1, whereby each valve is rotated in its 30 cylinder as indicated by the arrows, Fig. 3, and at a speed of one-sixth that of the crankshaft; in the engine illustrated, the gear ratio between the crankshaft and the shaft 45 being one and one-half to one and the gear ratio between the pinions and the 35 ring gears being four to one.

Specifically assuming the piston of any cylinder at the top of its stroke, as at the end of the exhaust stroke, the valve thereof 40 is timed whereby one of the valve ports will lie approximately midway between the cylinder ports 12 and 13. As rotation of the crankshaft causes the piston to move downwardly, the valve progresses to uncover 45 simultaneously the two intake ports 11 and 13 of the cylinder and a charge is induced into the cylinder. At the beginning of the succeeding upward stroke of the piston, the valve progresses to close simultaneously the 50 intake ports, and the exhaust port being also closed, the contents of the cylinder are compressed between the piston head and the cylinder head. As the piston reaches the 55 top of its stroke a spark is effected in the usual manner at the terminals of the spark plug, the compressed charge is ignited and the piston forced downwardly under the resulting great combustion or expansion pressure. As the piston nears the bottom 60 of this power stroke the valve progresses

to uncover the exhaust port 12 which is of sufficient size to remain uncovered during the succeeding upward stroke of the piston during which time the products of combustion are forcibly ejected from the cylinder. The four stroke cycle is thus completed and the operations described are repeated.

Each cam 43 is a triple cam, i. e., the contour formation is thrice repeated on the periphery of each ring gear. The result is that at all times each ring gear will bear upon each of its set of rollers, and when rotated by its pinion will receive a relatively slight longitudinal motion, allowed by the overhead clearances 52. Since the gear teeth are helical, longitudinal ring gear motion effected by such cam action will produce corresponding rotational variations of motion; so that the speed of rotation of the ring gears and therefore of their valves will receive increments and decrements according to the cam formation provided. The cam contours and the timing of the parts are such that the increments will be applied to the valves in maximum amounts as the functioning ports thereof are, preferably, midway overlying the adjacent cylinder port edges; whereby each valve is at its maximum speed during both port opening and closing operations. And, likewise, the arrangement 50 is preferably such that each valve will be at its minimum rotational speed at such instants when each cylinder port is fully open. Preferably also, in order to reduce the maximum tooth load, a maximum decrement period is arranged at the instant of ignition or of maximum combustion chamber pressure. The result is that a much improved valve characteristic is obtainable over that possible with a simple constant rotational 55 valve speed. A further advantage is that the relatively slight longitudinal valve motion effectively serves to prevent cutting of the valves against their seats in the cylinder walls.

By the cylinder head arrangement and proportions indicated, it will be observed that each combustion chamber is substantially equi-dimensional in two planes, i. e. in the vertical and lateral directions; and 60 is substantially symmetrical about a vertical plane longitudinal with the cylinder block. It will be noted also that the spark plug location is precisely central with respect to the horizontal section of the combustion chamber. Further, all of the fixed combustion chamber walls have curvature approximating a spherical formation. Thus 65 a very close approximation to the ideal spherical form of combustion chamber is attained.

It is also to be noted that two inlet ports are provided for each cylinder and that, with particular reference to Fig. 2, their 70 direction of entry into the combustion chamber

ber is such as to produce more or less of a pair of intersecting jets tangent to the curved longitudinal face of the cylinder head and impinging upon each other centrally of the face. Moreover, with reference to Fig. 1, the direction of inflow will be generally upwards and hence toward the location of the spark plug electrodes. Thus any tendency to stratification will be in favor of the richest or least dilution of mixture in the region of the spark plug electrodes. On the other hand, by employment of a single exhaust port there is the least resistance to out-flow of the products of combustion, and the least cylinder area surrounding the exhaust passage is exposed thereto.

By spacing the cylinder ports as indicated, a maximum cylinder head masking effect is possible, i. e., practically two-thirds of the head end portion of each valve at the elevation of the cylinder ports is fully protected by its cylinder head from the heat of combustion. Further, the two intake ports of each cylinder being spaced at 120° apart, the unbalanced pressure effect on the valve is largely offset. Also, by employing the number and arrangement of cylinder and valve ports described, an ideal valve opening cycle is obtained. It is known in the art that it is possible to employ a higher exhaust gas velocity than inlet velocity. With the dimensions shown the inlet velocity will be about 50% less than the exhaust velocity, which is an ideal condition here since inlet velocity is not relied upon to effect turbulence, turbulence being insured by the transverse face of the cylinder head cooperating with the piston head, as fully described in my copending application, to which reference has been made.

The dimensions of the ports longitudinally of the cylinder being so much greater than the port widths, the port openings are not particularly affected by the relatively slight movement of the valve in the longitudinal direction.

In the modified form of cylinder head appearing in Figs. 6 and 7, the cylinder head is cut away so that the face 32a thereof, instead of being of cylindrical form as the surface 32 in the type of head already described, is generally conical, the edges 53 of the head, however, being vertical and adjacent the inlet valve edges as before. The transverse face 31a is of considerably less area but still sufficient to cooperate with the piston and effect the desired turbulence.

Adjacent the spark plug 23a is a finger 54 extending longitudinally of the cylinder within the valve and terminating approximately at the elevation of the face 31a. The finger 54 has a hollow 55 in communication with the water jacket compartment

whereby the same is cooled. In Fig. 7 the valve 27a is shown substantially in its position at the instant of ignition. The finger 54 will be seen to extend peripherally along but clearing the inner face of the valve between an edge of the cylinder exhaust 12a and medially overlying the valve port 33a. Thus at the time of ignition any combustible gases lying within the port 33a will be burned before the valve is moved to progress its port 33a to overlie the finger 54. Thus when continued movement of the valve advances the port to open the exhaust valve, the finger 54 protects the exposed cylinder surface adjacent the exhaust port, and only products of combustion pass from the space within the port 33a into the exhaust passage.

In the modification shown in Figs. 8 to 11 the plugs or buttons 39a are substituted for the button 39, and are formed with their key portions located eccentrically of their head portions the key portions being in the shape of truncated cones each having its projected apex lying in the axis of the cylinder when the parts are assembled. The notches 35a are tapered inwardly to fit the key portions as indicated, instead of having parallel sides as have the notches 35. When this modified form of button is employed the valve is allowed a variant from the longitudinal irregularity of the ring gear movement, the buttons 39a shifting in their depressed seats 44 and acting as links through which the valve is pulled around by the ring gear whereby vibration due to longitudinal valve movement is much reduced.

Disassembly will be as follows: removal of any cylinder head and piston allows access to the corresponding valve which upon elevation to align the openings 34 thereof with the depressions 44 of its ring gear allows removal of the plugs 39 whereupon the valve may be withdrawn upwards from the cylinder. Removal of the valve releases the ring gear which may be moved laterally, rolling upon the adjacent ring gear with which it meshes, and outwards through the opening 48 (the cover 49 being removed) whereupon the roller assembly including the roller ring and band, may be inspected or removed and access had to the corresponding pinion.

What I claim is:

1. In an internal combustion engine, a cylinder having a pair of inlet ports adjacent the head end thereof, and an exhaust port therebetween, said cylinder ports being arranged adjacent the head end of said cylinder and grouped in a relatively small area, and a valve arranged for rotational movement in said cylinder and having ports equally spaced about the head end thereof, said

inlet ports being spaced apart correspondingly with the valve port spacing.

2. In an internal combustion engine, a cylinder having ports arranged adjacent the head end thereof, one of said ports communicating with an exhaust passage, a valve arranged for rotational movement in said cylinder to control said ports, and a head for said cylinder having a projection extending adjacent said exhaust port and means for cooling said portion.

3. In an internal combustion engine, a cylinder, a valve arranged for rotational movement in said cylinder and having ports equally spaced about the head end thereof, said cylinder having a pair of intake ports arranged to be opened and closed simultaneously by two of said valve ports, and having an exhaust port between said intake ports, and a head for said cylinder having a portion extending within said valve and provided with a face extending between and alongside said intake ports and adapted to direct together streams of flow entering said cylinder through said intake ports, whereby a turbulence will be set up within said cylinder.

4. In an internal combustion engine, a cylinder having a combustion chamber portion, and a pair of inlet ports arranged in a side wall portion thereof, cylindrical valve means arranged to control said ports, a piston movable in said valve means, and a head for said cylinder having a portion extending within said valve means, and having a face extending between and alongside said ports, and adapted to direct together streams of flow entering through said ports to set up a turbulence in a transverse plane, and having a face adapted to cooperate with the head of said piston to set up a turbulence in longitudinal planes.

5. In an internal combustion engine having a ported combustion chamber portion, the exhaust port area being appreciably less than the inlet port area, a valve arranged for revolution to control the ports, and driving means for said valve arranged to increase the speed thereof as the exhaust port area is opened and closed by the valve, above the mean valve speed.

6. In an internal combustion engine having a cylinder with a plurality of ports grouped in a relatively small area on one side thereof, a sleeve valve arranged in said cylinder to control said ports, a hollow head for said cylinder having a portion extending within said valve, with a mask portion of substantial volume projecting into the zone of said ports to mask that valve portion therein and outside of said area, and cut-away on the side of said area to form a face of concavity similar with that of said area and extending generally across said cylinder whereby a combustion chamber symmetrical

about a longitudinal axis is formed between said face and said area, and combustion-effecting means arranged in said head in a position to be intersected by said axis.

7. In an internal combustion engine having a cylinder with a plurality of ports grouped in a relatively small area on one side thereof, and comprising a pair of inlet ports spaced at 120° in said cylinder, with an exhaust port therebetween, a sleeve valve arranged for rotational movement in said cylinder, and having three ports equally spaced thereabout in the zone of said cylinder ports, and a head for said cylinder having a portion extending within said valve, with a mask portion of substantial volume projecting into said port zone to mask that valve portion therein and outside of the cylinder port area, and cut-away on the side of said area to form a concave face extending generally across said cylinder whereby a combustion chamber having concave walls is formed between said face and said area.

8. In an internal combustion engine having a ported surface and a valve arranged for rotary movement to control the port thereof, driving means for said valve and including rotating members having helical interengaging portions in driving and driven relation, and means for periodically moving one of said members longitudinal of its axis to correspondingly vary the rotational speed of said valve.

9. In an internal combustion engine having a ported cylinder and a valve arranged for revolution therein to control the ports thereof, driving means for said valve and including rotating members having helical intermeshing teeth, said valve being associated with the driven of said members for movement therewith, and means for effecting longitudinal components of valve movement, whereby the rotational valve speed is correspondingly varied.

10. In an internal combustion engine having a ported cylinder and a valve arranged for revolution therein to control the ports thereof, driving means for said valve and including rotating members having helical intermeshing teeth, and cam means associated with one of said members to control its relation with the other member whereby the speed of the valve will be caused to vary.

11. In an internal combustion engine having a ported cylinder and a valve arranged for revolution therein to control the ports thereof, driving means for said valve and including rotating members having helical intermeshing teeth, said valve being associated with the driven of said members for movement therewith, and cam means associated with said member to advance the same against the other member in timed relation with the valve travel, whereby said valve will have longitudinal components of

movement and its rotational speed will vary in timed relation with the opening and closing of said ports.

12. In an internal combustion engine having a ported cylinder and a valve arranged for revolution therein to control the ports thereof, driving means for said valve and including rotating members having helical intermeshing teeth, and cam means associated with one of said members to advance the same against the other member as said ports are opened and closed by the valve, whereby port-opening and port-closing valve speeds are greater than mean valve speed.
13. In an internal combustion engine having a ported cylinder and a valve arranged for revolution therein to control the ports thereof, driving means for said valve and including rotating members having helical intermeshing teeth, and cam means associated with one of said members to control its relation with the other member and arranged to allow recession of said associated member during the combustion period in said cylinder whereby the valve speed during said period is less than the mean valve speed.

14. In an internal combustion engine, a ported cylinder, a sleeve valve arranged for control of the cylinder ports, a valve actuating member positioned about and having driving relation with said valve, said cylinder having a transverse opening adapted to allow removal of said actuating member dependent upon removal of said valve therefrom, and having bearing surfaces for said valve on both sides of said actuating member.

15. In an internal combustion engine, a ported cylinder, a valve adapted for rotational movement to control the ports thereof, a valve driving member arranged for rotational movement with a longitudinal variant thereof, and driving connections between said valve and said driving member and adapted to cause said valve to follow said driving member but allow limited variation therefrom in motion.

16. In an internal combustion engine having a plurality of ported combustion chambers, and for each a sleeve valve arranged for revolution to control the ports thereof, driving means for said valves and including means for individually increasing the port opening and port closing speeds of the valves.

17. In an internal combustion engine having a plurality of ported combustion chambers and for each a valve arranged for revolution to control the ports thereof, driving means for said valves and including a ring gear for each valve, a shaft, a plurality of helical gears on said shaft each meshing with one of said ring gears, and means for effecting individual longitudinal adjustment

of the several ring gears periodically in the engine cycle to vary the instant speed of one of said valves independent of that of another.

In testimony whereof I hereby affix my 70 signature.

FRANK R. HIGLEY.
